UNITED STATES PATENT OFFICE

JOHN E. RIGALI, OF CHICAGO, ILLINOIS, ASSIGNOR TO DAPRATO STATUARY COMPANY,
OF CHICAGO, ILLINOIS, A CORPORATION OF ILLINOIS

DESIGN FOR A DEVICE FOR DESIGNATING A PLACE OF WORSHIP

Application filed February 13, 1931. Serial No. 38,643. Term of patent 14 years.

To all whom it may concern:

Be it known that I, JOHN E. RIGALI, a citizen of the United States, residing at Chicago, in the county of Cook and State of Illinois, have invented a new, original, and ornamental Design for a Device for Designating a Place of Worship, of which the following is a specification, reference being had to the accompanying drawings, forming a part hereof.

I claim:

The ornamental design for a device for designating a place of worship substantially as shown.

JOHN E. RIGALI.
